HAROLD F. PAGET, OF PHILADELPHIA, PENNSYLVANIA, ASSIGNOR TO HAINES HOSIERY MILLS INC., OF PHILADELPHIA, PENNSYLVANIA, A CORPORATION OF PENNSYLVANIA

WELT CLOSING MECHANISM FOR FULL FASHIONED KNITTING MACHINES

Application filed October 5, 1931. Serial No. 566,833.

This invention relates to mechanism useful in connection with full fashioned knitting machines to automatically close the welt tops of the stocking blanks produced on such machines.

In a previous application, Serial No. 430,566, filed by Joseph Haines, Jr., on February 24, 1930, Patent No. 1,826,661, is disclosed an automatic welt closing mechanism 10 in which latch hook welt bars, after the knitting of suitable lengths of welt fabric, were attached to the dipping frames of the fashioning mechanism of the machine, and the initially knit course of fabric loops held by 15 the welt bar hooks, transferred to the needles of the machine incident to the performance by the said fashioning mechanism of a narrowing cycle. Means were included in the arrangement for eliminating one of the two 20 usual dips of the narrowing frame of the fashioning mechanism to predetermine contact of the welt bar hooks with the needles but once for each welt closing operation.

My invention has for its chief aim to accomplish the same end, to wit, automatic welt closure, through modification of the press movement of the needle bars of the knitting machine to suit the usual movements of the narrowing frame of the machine likewise to 30 the end of predetermining contact of the needles but once during performance of a narrowing cycle by the fashioning mechanism.

A further object of my invention is to 35 secure the foregoing desideratum in an automatic welt closing mechanism having the form of a simple attachment which is readily incorporable in standard types of full fashioned knitting machines without requiring structural alterations in them or interfering with their normal mode of operation.

Another object of my invention is to provide in connection with automatic welt closing mechanism, control means whereby the 45 mechanism is brought into action concurrently with the initiation of a narrowing cycle of the fashioning mechanism for the purposes of automatic welt closure.

My invention is also directed in part to 50 toward provision, in connection with welt bars

designed for use in automatic welt closing mechanism, of means adapted to hold the fabric loops to a definite position on the shanks of the welt bar hooks to insure their depression below the sinkers of the knitting machine incident to transfer of the fabric loops to the knitting needles, and moreover, adapted to yield to being displaced by the sinkers of the machine upon advance of the latter to restrain the fabric while the welt bars are withdrawn.

Other objects and attendant advantages of this invention will be manifest from the detailed description following when taken with the attached drawings, wherein Fig. I is an illustration showing, in front elevation, a fragmentary portion of a full fashioned stocking knitting machine conveniently embodying the present improvements.

Fig. II is a cross section of the machine viewed as indicated by the arrows II—II in Fig. I.

Fig. III shows another cross section of the machine, taken as indicated by the arrows III—III in Fig. I; and Figs. IV and V are detail views.

Figs. VI, VII, VIII and IX are diagrammatic illustrations showing the manner in which the stocking welt is closed in accordance with my invention.

The knitting machine herein illustrated is, generally speaking, of standard design, each of its needle bars 10 being moved up and down relative to the sinkers 12 and knockovers 13 incident to the formation of fabric loops in the well known manner, by a rotary cam (not shown) on the cam shaft 14, through the instrumentality of levers 15 and 16 secured to a longitudinal rock shaft 17 with bearing support in the transverse frame members whereof two are indicated at 18, 19. At the same time, and also after well known practice, the needle bar 10 is moved in and out to effect closure of the needle beards, through rocking of said bar about fulcrum connections at 20 with the levers 15, through the usual connections indicated at 21, 22 and 23. Of these, the arm 23 is provided with a roller 24 which is ordinarily maintained in operative contact with the usual rotary

needle press cam 25, Fig. I, on the cam shaft 14, through the influence of a tension spring 26 upon said arm. The dipping frame of the fashioning mechanism of the machine is comprehensively designated by the numeral 27, its longitudinal rod 28 being supported after common practice by a number of upwardly curved arms 29 that reach forward from a horizontal rock shaft 30 at the back of the machine. The dipping frame 27 is moved up and down in the known manner incident to the performance of the narrowing cycles of the fashioning mechanism, by virtue of link connections 31 with cam operated levers, not shown. The usual loop transfer point combs employed in narrowing the fabric are shown at 32, 33—whereof there is a pair provided for each bank of the needles—being respectively secured to horizontal slide rods 34, 35 which are shiftable back and forth in guide brackets 36 pendant from a longitudinal rod 28 of the dipping head 27. All the usual phases of the knitting performed by the machine are subject to the governance of a pattern chain indicated at 38 in Fig. I, the same being trained about a drive sprocket 39 rotating on a stud shaft 40 which is supported by a bracket 41 on the frontal longitudinal bottom rail 42 of the machine frame. The opposing rotary cams which are instrumental in shifting the cam shaft 14 to the right, as required for determining the narrowing cycles of the machine, are indicated at 43 and 44 in Fig. I; and the rollers which cooperate with these cams, at 45 and 46, the said rollers being carried by a spring pulled arm 47 fulcrumed at 48 on the machine frame. The trip latch member 49 for the roller arm 47 is ordinarily actuated by buttons 38a on the measuring chain 38; and, as usual, said member is provided with a stud handle 50 whereby it may be manually actuated, when required, to initiate a narrowing cycle.

The means shown at 51 for detachably securing the latch hook welt bars 52 to the point comb bars 34, 35 on the dipping frame 27 of the narrowing mechanism are of a design and construction identical to that described in the Haines' application hereinbefore referred to.

In order to adapt a standard full fashioned stocking knitting machine equipped as above described, for the purposes of automatic welt closure in accordance with my invention, I provide mechanism as follows: Mounted on the cam shaft 14 immediately to the left of the usual press cam 54 employed during the ordinary narrowing phases of the knitting is an auxiliary split press cam 55. As clearly shown in Fig. II, this auxiliary press cam 55 has a concentric circumferential edge portion 55a which substantially comprehends a semi-circle, and two spaced rises 55b and 55c whereof the function will be later explained: Slidable in guide brackets 56 and 57 separately secured to the cross frames 18 and 19 of the machine is a horizontal shifter rod 58 with a fork 59 at one end thereof engaging the roller 24 of the needle bar actuating arm 23, which roller, in the present instance is slideable endwise on its supporting axis 24a, see Figs. I, II and V. The shifter rod 58 is subject to a spring 60 which serves to yieldingly urge the said rod toward the right in Fig. I, so that a collar 61 thereon is held in contact with the corresponding side of the guide bracket 56, the roller 24 of the needle bar actuating arm being thereby maintained in the plane of the usual press cam 25 during the regular knitting periods of the machine.

The means relied upon to actuate the shifter rod 58 includes a pair of special rotary cams 62, 63 which are shown in Fig. I as being mounted on the cam shaft 14 leftward of the transverse frame 18. Adapted to cooperate with the side face 62a of the cam 62, is a roller 64 which is carried at one end of an arm 65 whereof the opposite end has a forked connection with a finger 66 on the shifter rod 58. From Figs. I, III and IV it will be observed that the roller arm 65 is pivoted at 67 to a swivel member 68, which latter is in turn fulcrumed on a stud 69 projecting laterally from an upright bracket 70 on the machine frame rail 42. The roller arm 65 is thus supported with capacity to swing on its own axis 67 in following the configuration of the cam 62, as well as with capacity to swing toward and away from the said cam about the stud 69. Normally, the roller arm 65 is held retracted in the position illustrated against the pull of a spring 71, by a trippable latch member 73 fulcrumed at 74 at the front of the bracket 70, said arm being moved to such position at the completion of each welt closing operation as herein-after more fully described, through action of the peripheral rise 63a of the cam 63 upon an upward roller arm 75 of the swivel member 68.

At 76 in Fig. I is shown a pedal whereby the latch members 49 and 73, associated with the roller arms 47 and 65 respectively associated with the rotary cams 43, 44 and 62, 63 may be manually tripped. As illustrated the pedal 76 is pivoted on a fulcrum bolt 77 let into the front of the machine frame rail 42, and normally held against a stop 78 by means of a spring 79. A link 80 connects a radial lug 76a of the pedal 76 with the latch member 73; while another radial lug 76b of the said pedal is pivotally coordinated with a thrust rod 81 which is guided for up and down movement in a fixed bearing lug 82 and which has its upper end laterally turned, as at 81a to underreach the stud handle 50 of the latch member 49.

As an aid to insure depression of the fabric loops beneath the sinkers 12 of the machine

for retention by the latter as the latched hooks 52a of the welt bars 52 are withdrawn at the termination of a welt closing operation, I have fitted the said bars with loop aligning members 85. As shown in Figs. I, II, VII and VIII each such loop aligning member 85 has the form of a straight edge with arms 86 pivotally connected to the welt bar at 87. The precise operation of the provisions just described will be presently set forth in greater detail.

The operation of my improved welt closing apparatus is as follows:

Let it be assumed that sufficient lengths F of welt fabric have been knit; that the welt bars 52 have been attached to the dipping frame 27 of the narrowing mechanism of the machine by the means 51; and that rods 90 have been placed within the folds of the welts and connected to the draw straps 91 of the take-up rollers 92 as shown in Figs. I and II—all these operations having been performed with the machine quiescent and its various parts in the positions illustrated. With these preparations made, the operative restarts the machine, and at the same time depresses the control treadle 76. As a consequence, the latch members 49 and 73 are concurrently tripped, and the roller arms 47 and 65 thereby released to the action of their springs. Immediately upon entry of the roller 45 on the arm 47 between the cams 43, 44, the cam shaft 14 is moved endwise toward the right in Fig. I to initiate a narrowing cycle in the well known manner. Attendant upon such endwise movement of the cam shaft, the roller arm 65 released as just explained, is acted upon by the cam 62, whereby the shifter rod 58 is moved toward the left and the roller 24 of the needle bar actuating arm 23 placed in the plane of the auxiliary press cam 55. Therefore, during the ensuing rotation of the cam shaft 14 in the direction of the arrow in Fig. II, the needle bar 10 is dependent for its in and out movement, upon the auxiliary press cam as the machine performs the narrowing cycle. During the first dip of the frame 27, the latched hooks 52a of the welt bars 52 are brought down from the position shown in Figs. I and VI to the position of Fig. VII into overlapping relation with the needles 10a; but at this stage in the operation, the roller 24 of the needle bar actuating arm 23 rides the concentric low portion 55a of the auxiliary press cam 55, the needles being accordingly held away from the welt bar hooks as illustrated in Fig. VII. However, as the frame 27 makes its second dip, the high spot 55b of the auxiliary press cam 55 causes the needles 10a to be pressed into contact with the welt bar hooks 52a after the manner shown in Fig. VIII, the initially knit course of fabric loops L held by the welt bar hooks being incidently depressed positively to a level somewhat be-

low the sinkers 12 by the straight edge member 85. As the narrowing cycle of the machine continues, the sinkers 12 are simultaneously advanced (as usual during narrowing cycles) to the dot and dash line position shown in Fig. VIII over the top layer of the fabric F. The welt bar hooks 52a and the needles 10a are thereupon concurrently elevated for a time until the beards of said needles have passed through the loops L. After this has been accomplished, the welt bar hooks are elevated at a more rapid rate than the needles 10a and thereby withdrawn from the latter as in Fig. IX. By influence of the second rise 55c, the needles 10a are restored to the normal position relative to the sinkers 12, the said cam rise 55c being as shown in Fig. II coincident with the concentric idling portions of the usual press cams 54 and 25 so that the roller 24 of the needle bar actuating arm can be moved back into the plane of the cam 25 at the termination of the narrowing cycle, which latter is determined through outward displacement of the roller arm 47 from the cams 43 and 44 immediately upon movement of the cam shaft to the left by said cams. Also, as the cam shaft completes its revolution, the high spot 63a of the cam 63 causes the roller arm 65 to be displaced from the cam 62 so that the spring 60 is permitted to move the shifter rod 58 toward the right in Fig. I with attending restoration of the roller 24 of the needle bar actuating arm 23 into the province of the usual press cam 25 in readiness for subsequent continuation with regular knitting by the machine.

From the foregoing, it will be seen that I have provided an automatic welt turning mechanism consisting of a few simple parts which are readily attached to a standard full fashioned stocking machine without requiring structural alterations; and moreover that the said mechanism does not in any way interfere with the usual functions of the machine.

Having thus described my invention, I claim:

1. Automatic welt closing mechanism for full fashioned knitting machines comprising a welt bar and means whereby it may be detachably secured to the dipping frame of the fashioning mechanism of the machine; and means auxiliary to the usual needle press cams of the machine to determine contact of the needles with the welt bar hooks incident to but one of the two usual dips of the narrowing frame as the fashioning mechanism is caused to perform a narrowing cycle for the purposes of automatic welt closure.

2. Automatic welt closing mechanism for full fashioned knitting machines having the form of an attachment applicable to such machines without necessitating any alteration in their construction or normal mode of operation, the said welt closing mechanism com-

prising a welt bar and means whereby it may be detachably secured to the dipping frame of the fashioning mechanism of the machine; and means auxiliary to the usual needle press 30 cams of the machine to determine contact of the needles with the welt bar hooks incident to but one of the two usual dips of the narrowing frame as the fashioning mechanism is caused to perform a narrowing cycle for the purposes of automatic welt closure.

3. Automatic welt closing mechanism for full fashioned knitting machines comprising a welt bar and means whereby it may be detachably secured to the dipping frame of the 15 fashioning mechanism of the machine; a rotary cam, auxiliary to the usual needle press cams of the machine to determine contact of the needles with the welt bar hooks incident to but one of the two usual dips of the narrowing frame as the fashioning mechanism is caused to perform a narrowing cycle for the 20 purposes of automatic welt closures; and means for shifting the roller of the usual needle bar actuating arm into the province of the 25 said auxiliary cam upon initiation of the narrowing cycle.

4. Automatic welt closing mechanism for full fashioned knitting machines comprising a welt bar and means whereby it may be detachably secured to the dipping frame of the 30 fashioning mechanism of the machine; a rotary cam auxiliary to and mounted on the cam shaft of the machine to the left of the two usual needle press cams, the said auxiliary 35 cam adapted to determine contact of the needles with the welt bar hooks incident to but one of the two usual dips of the narrowing frame as the fashioning mechanism is caused to perform a narrowing cycle for the 40 purposes of automatic welt closure; and means for shifting the roller of the needle bar actuating arm of the machine leftward into the province of the said auxiliary cam 45 concurrently with shifting of the cam shaft rightward upon initiation of the narrowing cycle.

5. Automatic welt closing mechanism for full fashioned knitting machines, comprising a welt bar and means whereby it may be detachably secured to the dipping frame of the 50 fashioning mechanism of the machine; means auxiliary to the usual needle press cams of the machine to determine contact of the needles with the welt bar hooks incident to but one 55 of the two usual dips of the narrowing frame during the performance of a narrowing cycle by the fashioning mechanism; and means operative to initiate the narrowing cycle and to concurrently render the auxiliary cam 60 aforesaid active for the purposes of automatic welt closure.

6. Automatic welt closing mechanism for full fashioned knitting machines, comprising a welt bar and means whereby it may be 65 detachably secured to the dipping frame of

the fashioning mechanism of the machine; a rotary cam auxiliary to the usual needle press cams of the machine, to determine contact of the needles with the welt bar hooks incident to but one of the two usual dips of the narrowing frame as the fashioning mechanism is caused to perform a narrowing cycle; and means for shifting the roller of the needle bar actuating arm leftward along its supporting axis into the province of the said auxiliary 70 cam concurrently with shifting of the cam shaft rightward upon initiation of the narrowing cycle, including a shifter rod, and another cam on the cam shaft for actuating the shifter rod.

7. Automatic welt closing mechanism for full fashioned knitting machines, comprising a welt bar with means whereby it may be detachably secured to the dipping frame of the 75 fashioning mechanism of the machine; a rotary cam auxiliary to the usual needle press cams of the machine to determine contact of the needles with the welt bar hooks incident to but one of the two usual dips of the narrowing frame as the fashioning mechanism is caused to perform a narrowing cycle for the 80 purposes of automatic welt closure; and means for shifting the roller of the needle bar actuating arm leftward along its supporting axis into the province of the said auxiliary cam concurrently with shifting of the cam shaft rightward upon initiation of the narrowing cycle, including a shifter rod, a separate cam on the cam shaft adapted to influence a normally retracted actuating member for the shifter rod, and means for moving said member into operative relation with its cam.

8. Automatic welt closing mechanism for full fashioned knitting machines, comprising a welt bar and means whereby it may be detachably secured to the dipping frame of the 85 fashioning mechanism of the machine; means auxiliary to the usual needle press cams of the machine to determine contact of the needles with the welt bar hooks incident to but one of the two usual dips of the narrowing frame incident to the performance by the 90 fashioning mechanism of a narrowing cycle; and means for tripping the usual latch means of the machine controlling the initiation of a 95 fashioning cycle, and for concurrently rendering operative the auxiliary means aforesaid for the purposes of automatic welt closure.

9. Automatic welt closing mechanism for full fashioned knitting machines, comprising a welt bar with means whereby it may be detachably secured to the dipping frame of the 100 fashioning mechanism of the machine; a rotary cam auxiliary to the usual needle press cams of the machine to determine contact of the needles with the welt bar hooks incident to but one of the two usual dips of the narrowing frame as the fashioning mechanism 105

is caused to perform a narrowing cycle for the purposes of automatic welt closure; means for shifting the roller of the usual needle bar actuating arm along its axis into the province of the said auxiliary cam; a separate cam on the cam shaft adapted to influence an actuating member for the shifting means; a latch member for normally holding the actuating member retracted from its cam; and means for tripping the aforesaid latch means concurrently with the usual latch means of the machine controlling the initiation of a fashioning cycle, with attendant actuation of the needle bar by the auxiliary cam during automatic welt closure.

10. A welt bar useful in connection with automatic welt turning mechanism for full fashioned knitting machines, having latched fabric loop engaging hooks, and a loop aligning member for definitely depressing the fabric loops below the sinkers of the knitting machine incident to a welt closing operation, the said loop aligning member being attached to the welt bar with capacity for yielding to 25 displacement by the sinkers upon advance of the latter over the loops.

11. A welt bar useful in connection with automatic welt turning mechanism for full fashioned knitting machines, having latched fabric loop engaging hooks; and a loop aligning member for definitely depressing the fabric loops below the sinkers of the machine incident to a welt closing operation, the said loop aligning member being pivotally connected to the welt bar with capacity for yielding to lateral displacement upon advance of the sinkers over the loops.

In testimony whereof, I have hereunto signed my name at Philadelphia, Pennsylvania, this first day of October, 1931.

HAROLD F. PAGET.
